[57] CLAIM

The ornamental design for a facsimile transceiver, as shown and described.

DESCRIPTION

FIG. 1 is a top, front and right side perspective view of a facsimile transceiver showing our new design; FIG. 2 is a top, front and left side perspective view thereof;

FIG. 3 is a top plan view thereof;

FIG. 4 is a front elevational view thereof;

FIG. 5 is a right side elevational view thereof;

FIG. 6 is a bottom plan view thereof;

FIG. 7 is a rear elevational view thereof; and

FIG. 8 is a left side elevational view thereof.

The broken line showing is for illustrative purposes only and forms no part of the claimed design.
